(57) **CLAIM**

The ornamental design for a door facing, as shown and described.

DESCRIPTION

FIG. 1 is a front elevational view of our design, with the rear being a mirror image thereof;

FIG. 2 is a cross sectional view taken along the line 2—2 of FIG. 1 and viewed in the direction of the arrows;

FIG. 3 is an enlarged fragmentary cross-sectional view, taken from the left end of FIG. 2;

FIG. 4 is a cross sectional view taken along the line 4—4 of FIG. 8 and viewed in the direction of the arrows; and
FIG. 5 is an enlarged fragmentary cross sectional view, taken from the right end of FIG. 4;

FIG. 6 is a cross sectional view taken along the line 6—6 of FIG. 8;

FIG. 7 is an enlarged fragmentary cross sectional view, taken from the right of FIG. 6; and,

FIG. 8 is a front elevational view.
